UNITED STATES PATENT OFFICE

WILBUR B. FOSHAY AND GOTTLIEB R. MAGNEY, OF MINNEAPOLIS, MINNESOTA, AS
SIGNORS TO W. B. FOSHAY CO., OF MINNEAPOLIS, MINNESOTA

DESIGN FOR A BUILDING

Application filed February 1, 1929. Serial No. 29,871. Term of patent 14 years.

To all whom it may concern:

Be it known that we, WILBUR B. FOSHAY and GOTTLIEB R. MAGNEY, citizens of the United States, residing at Minneapolis, in the county of Hennepin, and State of Minnesota, have invented a new, original, and ornamental Design for Buildings, of which the following is a specification, reference being had to the accompanying drawing, forming part thereof.

Fig. 1 is a side elevational view showing our new design.

Fig. 2 is a perspective view thereof.

We claim:

The ornamental design for a building, as shown.

In testimony whereof we hereunto affix our signatures.

WILBUR B. FOSHAY.
GOTTLIEB R. MAGNEY.
